United States Patent Office

Des. 219,569
Patented Dec. 29, 1970

219,569

CONFECTION

William N. Prifti, 106 Green St.,
Worcester, Mass. 01608

Filed Jan. 22, 1969, Ser. No. 15,444

Term of patent 14 years

Int. Cl. D1—02

U.S. Cl. D1—1

FIG. 3

FIG. 1

FIG. 2

FIG. 4

FIG. 1 is a side view of a confection, showing my new design;

FIG. 2 is an end view of the confection,

FIG. 3 is a plan view of the confection, and

FIG. 4 is a bottom view of the confection.

Both ends and both sides of the confection are the same.

I claim:

The ornamental design for a confection, as shown and described.
